ENGINE ANTI-STALL DEVICE

Harold A. Carlson, Brentwood, Mo., assignor to ACF Industries, Incorporated, New York, N.Y., a corporation of New Jersey

Application October 21, 1957, Serial No. 691,345

11 Claims. (Cl. 261—41)

This invention relates to internal combustion engines and more particularly to an anti-stall feature for internal combustion engines.

Internal combustion engines generally will not run properly below some definite minimum speed for a particular engine. When the speed of the engine falls below this minimum, from whatever cause, the engine is likely to stop running or, in other words, to stall. Many factors can cause engine speed to be reduced below the permissible minimum, thereby causing stalling. Included among these factors are very rapid deceleration, a reduction in pressure differential between the ambient pressure and the intake manifold pressure as may result from improper mixture ratio, improper ignition adjustment, an increase in altitude, or an unduly poor grade of fuel, to name but a few. It is common practice to provide internal combustion engines with anti-stall devices which usually operate responsive to a reduction in intake manifold pressure below a given minimum for a particular engine. However, it has been found that relying on intake manifold pressure to actuate anti-stall mechanisms is not entirely satisfactory. The maximum permissible intake manifold suction pressure must be sufficiently high to permit a wide range of ambient air pressure brought about by changes in altitude, engine condition, and the like, resulting in reduced sensitivity in actuation of the anti-stall mechanism. Furthermore, the engine may operate when the intake manifold pressure is relatively high because of the condition of the valves, piston rings, or other factors. Anti-stall mechanisms responsive to manifold pressure must be mechanically coordinated with throttle position so that they are operative only when the throttle is substantially closed to prevent their operation at open throttle under extremely heavy load conditions resulting in a relatively high intake manifold pressure.

It is therefore an object of this invention to provide an improved anti-stall mechanism for internal combustion engines.

Another object of this invention is to provide internal combustion engines with a more sensitive anti-stall feature.

Still another object of this invention is to provide an anti-stall feature which is simple and precise in operation.

Still another object of this invention is to provide an internal combustion engine with an anti-stall feature responsive to fuel pressure.

Additional objects and advantages will be apparent from the following description and drawings, in which:

Fig. 1 is a fragmentary partial sectional elevation view of an embodiment of the invention as applied to a carburetor.

Fig. 2 is a sectional elevation view of another embodiment of the invention applied to a carburetor similar to that illustrated in Fig. 1.

Briefly, the invention relates to an anti-stall feature for admitting additional air to the combustion area of an internal combustion engine, to prevent stalling of the engine under idling conditions, responsive to a drop in fuel

2

pressure below a predetermined minimum. For purposes of illustration, the invention is shown as applied to a carburetor. In the two disclosed embodiments, a pressure sensing diaphragm motor responds to a drop in fuel pressure to admit additional air to the intake manifold of an internal combustion engine. In the first embodiment, the throttle valve is opened an additional amount from its normal idle or closed position to admit more air and fuel around the throttle valve. In the second embodiment, an auxiliary valve is opened to permit additional air to flow through a by-pass around the throttle valve.

The invention will now be described in detail with particular reference to the aforementioned embodiments, but it is to be understood that the invention is applicable to internal combustion engines generally, irrespective of the fueling system, and is not to be limited to engines equipped with carburetors, but is equally applicable to other forms of fueling systems; for example, fuel injection systems.

Referring to Fig. 1, a carburetor 1 has a body 2 and a flange 3 for attachment to the induction manifold (not shown) of an internal combustion engine. The carburetor body is fitted with a cover 5 secured thereto by bolts 7. A portion of the bolts may pass through the body 2, flange 3, and into the intake manifold. An induction conduit 9 passes through the cover 5, body 2, and flange 3, and includes an air horn 11 formed integrally with the cover 5. The air horn contains the normal pivoted choke (not shown). A conventional temperature responsive choke control 13 is connected to a source of engine heat such as an exhaust manifold for maintaining the choke closed during the warm-up period. A float system includes an inlet 15, filter 16, and needle valve assembly 17, all in the cover 5, and a float 19 pivotally mounted in a fuel chamber 20 in the body 2. The float 19 will drop responsive to a drop in fuel level in the fuel chamber 20 to permit the needle valve assembly 17 to open and admit fuel through the inlet 15 to the fuel chamber 20. The fuel chamber is conventionally vented to maintain the pressure therein substantially atmospheric. A main or high speed orifice 25 in the bottom of the fuel chamber 20 opens into a main fuel passageway 27 fitted at one end with a nozzle 29 which discharges into a venturi cluster 31 in the induction passage 9. A passageway 33 through the body 2 connects the nozzle 29 and the fuel chamber 20 to prevent percolation. A metering rod 35 is fitted in the main orifice 25 and is responsive to an increase in engine speed to permit more fuel to enter the main fuel passageway 27. An idle tube 37 has an open lower end 38 for picking up fuel from the passage 27. After fuel is drawn into the tube 37 it passes through a conventional idle system which may include a by-pass, economizer, and bleed, and through a passageway system 40 to the idle ports 43 and 44. The lower idle port 44 is provided with an idle adjustment screw 45. A throttle valve 50 is fixed to a shaft 51 pivotally mounted in the flange portion of the induction conduit 9 and may be manually actuated in any conventional manner.

Referring now to Fig. 1, the dashed lines illustrate the throttle valve 50 in its normally closed or idle position, and corresponds to the position of the throttle valve 50 in Fig. 2. However, in Fig. 1 sufficient air must pass the closed throttle valve to form a combustible mixture, while in Fig. 2 the throttle valve may be tightly closed. Fixed on the throttle shaft 51 is a fixed lever 55 having a shoulder 56. Rotatably mounted on the throttle shaft is a rotatable lever 58 having a dog 59 for engaging the shoulder 56 on the fixed lever 55. A finger 61 on the rotatable lever 58 is freely received in a hole 63 in a rod end member 64 on a rod 65 journaled in an adjusting nut 67 threaded into an inner housing 71 of a pressure sensing diaphragm motor 72. The diaphragm motor in-

cludes an outer housing 73 with a diaphragm 74 clamped therebetween as by bolts 75. The diaphragm 74 is provided with conventional rigid washers 76 on either face thereof, and is secured to the rod 65 in any conventional manner as by a peened-over portion 79 of the rod. The inner housing 71 of the motor is provided with a cylindrical stop 80 to limit inward movement of the diaphragm 74. The outer housing 73 is similarly provided with stops 81 to limit outward movement of the diaphragm. The diaphragm 74 and inner housing 71 define an atmospheric chamber 84 having an atmospheric vent 85. The outer housing 73 and the diaphragm 74 define therebetween a pressure chamber 87 having an opening 88 into a double-ended coupling portion 89. A spring 91 is received on the rod 65 and engages a shoulder 92 on the rod and the adjusting nut 67. The pressure sensing diaphragm motor 72 is rigidly mounted on the flange 3 by a bracket 94 secured to the flange by bolts 95. A nut 96 threaded on the casing rigidly secures the motor to the bracket.

The fuel system includes a tank 97, a fuel pump 98, the pressure sensing diaphragm motor 72, and the fuel inlet 15 in the carburetor cover 5, connected in series by conduits. The only requirement of the pump 98 is that the delivered fuel pressure from the pump in the idle speed range be proportionate to the engine speed. Suitable pumps of this type are shown in United States Patents Numbers 2,786,423 and 2,803,265, and usually deliver 2-5 p.s.i. fuel pressure at idle speed.

The operation of the embodiment illustrated in Fig. 1 is as follows: With the engine operating at idle speed, the position of the throttle valve 50 will be as shown by the dashed lines and the throttle will be in the normal closed position. Fuel is drawn from the tank 97 through the pump 98 and then through the connection 89 on the pressure sensing diaphragm motor 72 and into the fuel inlet 15 of the carburetor 1. Normal pressure of the fuel in the pressure chamber 87 of the pressure sensing motor forces the diaphragm 74 to the position shown. The linkage between the diaphragm 74 and the rotating lever 58 on the throttle shaft 51 is such that the dog 59 engages or nearly engages the shoulder 56 of the fixed lever 55 on the throttle shaft. Should the engine begin to stall, that is, should the engine speed fall sufficiently below the normal idle speed that the engine would be likely to die, the speed of the fuel pump 98 will likewise fall, resulting in a reduction in fuel pressure between the pump and the fuel inlet 15 in the carburetor. This reduction in pressure is, of course, reflected in the pressure chamber 87 of the pressure sensing diaphragm motor 72 and the spring 91 urges the diaphragm 74 outwardly to the position shown by the phantom lines 74'. This motion of the diaphragm is transmitted through the rod 65 and the rod end coupling 64 and finger 61 to rotate the rotating lever 58 counterclockwise to the position shown by the phantom lines 58'. The fixed lever 55 on the throttle shaft is rotated by the dog 59 to the position shown by the phantom lines 55' thereby rotating the throttle valve to the position shown by the phantom lines 50'. With the throttle cracked open in this manner, additional air is permitted to enter the engine, increasing its speed, as is well understood in the art to which this invention pertains. As the engine speed increases, the pump speed simultaneously increases resulting in a higher pressure in the pressure chamber 87 of the pressure sensing diaphragm motor again restoring the throttle to its normal idle position 50.

Referring now to the embodiment illustrated in Fig. 2, similar reference numerals indicate the same parts as in Fig. 1. The throttle valve 50 is in the idle or closed position. As illustrated, the throttle valve is tightly closed and any air passing into the engine intake manifold passes through the port 102 in the induction conduit 9, through the passageway 103 and into the manifold through a slot 104 in the bottom of the flange 3. An adjusting screw 106 is provided to permit adjustment of the quantity of

air passing through port 102. A passageway 108 extends upwardly into a chamber 109 which is connected with the induction conduit 9 by a passageway 110. The junction of the passageway 110 and the chamber 109 provides a seat 111 for a needle valve 112. The needle valve is tapered at one end 113 to engage the valve seat with a sealing fit. The other end of the valve is fixed to a flexible diaphragm 115 having reinforcing washers 116 on either side thereof. A compression spring 117 engages one of the washers 116 urging the diaphragm 115 outwardly. The diaphragm is clamped between a shoulder 120 on the carburetor body 2 and a clamping member 121 secured to the carburetor body in any conventional manner as by bolts. The clamping member 121 has a threaded passageway 122 communicating with the diaphragm 115 and defining a pressure chamber 123 for receiving a conduit 124 from the delivery side of the fuel pump 98.

The operation of the embodiment illustrated in Fig. 2 is as follows: When the engine is at normal idle speed the fuel pressure delivered into the pressure chamber 123 forces the needle valve 112 inwardly against the valve seat 111, preventing the entrance of air through the passageway 110. When the engine begins to stall, the pressure in the pressure chamber 123 will fall permitting the spring 117 to force the needle valve 112 outwardly admitting air through the passageway 110. The air flows through the chamber 109, the passageway 108, and past the port 102 adding to the air admitted therethrough, and then through the passageway 103 and the slot 104 into the engine intake manifold, thereby increasing the speed of the engine and the fuel pump 98, which increases the fuel pressure in the pressure chamber 123 closing the valve 112.

Although this invention has been described with particular reference to certain embodiments, features, structural details, and functions in keeping with the recited objects of the invention, various modifications and improvements will be apparent to one skilled in the art, and the invention is therefore not to be limited to such embodiments, features, structural details or functions except as set forth in the appended claims.

I claim:

1. In an internal combustion engine, the combination of, means for supplying air to said engine, means for supplying fuel to said engine above a minimum pressure when said engine is operating at normal idle speed, means for mixing said fuel and said air to form a combustible mixture, and means to provide additional air for said combustible mixture responsive to a drop in fuel pressure below said minimum pressure due to a decrease in engine idling speed.
2. In a carburetor, means for receiving fuel above a minimum pressure, an induction conduit having a mixture portion and a portion for admitting air to said mixture portion, and means responsive to a drop in fuel pressure to admit additional air to said mixture portion of said induction conduit when said carburetor is in the idle range.
3. In a carburetion system, means for supplying fuel above a minimum pressure to a carburetor, an induction conduit having a mixture portion and a portion for admitting air to said mixture portion wherein said fuel and said air are mixed, said mixture portion being defined by the portion of said induction conduit downstream from a substantially closed throttle valve in said induction conduit, and means for admitting additional air downstream from said throttle valve responsive to a reduction in fuel pressure below said minimum pressure.
4. In a carburetion system for an engine, means for supplying fuel above a minimum pressure to a carburetor, an induction conduit having a mixture portion and a portion for admitting air to said mixture portion, said mixture portion being defined by the portion of said induction conduit downstream from a substantially closed throttle valve in said induction conduit, and means to open said

70

throttle valve responsive to a drop in fuel pressure below said minimum pressure to admit additional air to the mixture portion of said induction conduit to prevent stalling of said engine upon a drop in fuel pressure.

5. In a carburetion system for an engine, means for supplying fuel to a carburetor at pressures varying as the speed of the engine during operation of the engine in the general vicinity of the idle speed, an induction conduit in said carburetor, a throttle valve in said induction conduit, means for discharging fuel into said induction conduit downstream from said throttle valve when said throttle valve is substantially closed and said engine is operating in the general vicinity of said idle speed, a pressure sensing diaphragm motor including a pressure chamber for actuating a diaphragm responsive to changes in the pressure of fuel delivered to said carburetor, and means interconnecting said diaphragm and said throttle valve to open said throttle valve when said engine is operating in the general vicinity of said idle speed and the pressure of said fuel drops below the pressure normally supplied when said engine is operating at said idle speed.

6. In a carburetion system for an engine, means for supplying fuel above a minimum pressure to a carburetor, an induction conduit having a mixture portion and a portion for admitting air to said mixture portion, said mixture portion being defined by the portion of said induction conduit downstream from a substantially closed throttle valve in said induction conduit, a by-pass having one end opening into a supply of air and the other end opening into said induction conduit downstream from said throttle for conveying air to said mixture portion, and means responsive to a reduction in said minimum fuel pressure to open a normally closed valve in said by-pass to permit additional air to flow through said by-pass and into the mixture portion of said induction conduit.

7. In a carburetion system for an engine, means for supplying fuel to a carburetor at pressures varying as the speed of the engine during operation of the engine in the general vicinity of the idle speed, an induction conduit in said carburetor, a throttle valve in said induction conduit defining a mixture portion in said induction conduit downstream from said throttle valve, means for discharging fuel into said mixture portion when said throttle valve is substantially closed and said engine is operating in the general vicinity of said idle speed, a by-pass having one end opening into a supply of air and the other end opening into said mixture portion for conveying air to said mixture portion, an air valve in said by-pass for controlling the amount of air delivered to said mixture portion, a pressure sensing diaphragm motor including a

pressure chamber for actuating a diaphragm responsive to changes in the pressure of fuel delivered to said carburetor, and means interconnecting said diaphragm and said valve to open said air valve when said engine is operating in the general vicinity of said idle speed and the pressure of said fuel drops below the normal pressure when said engine is operating at said idle speed.

8. In the carburetion system of claim 6, the first said end of said by-pass opening into said induction conduit upstream from said throttle valve.

9. In an internal combustion engine, the combination of, means for supplying air to the engine, pump means for supplying fuel to the engine, means to vary the output of said pump means with changes in engine speed within a certain range of engine speeds, means for mixing the air and fuel supplied by said first means and said pump, respectively, to form a combustible mixture for said engine, mixture control means operative within said certain range of engine speeds, and means connected to said pump means and said mixture control means for adjusting the mixture in accordance with changes in pump output.

10. In an internal combustion engine, the combination of, means for supplying a fuel-air mixture for proper operation of the engine within a certain range of engine speeds, means for controlling the speed within said speed range, a source of fuel for said first means, a pump connected with said source and supplying fuel under pressure to said first means, means to operate said pump at speeds variable with engine speed so that pump output changes within the certain range of engine speeds, and means connected with said pump and responsive to changes in pump output connected with and operating said means for controlling the engine speed.

11. In an internal combustion engine, the combination of, means for supplying a fuel-air mixture for operation of the engine within a certain range of engine speeds, means for controlling the fuel ratio delivered by said means, a source of fuel for supplying said first means, a pump connected with said source of fuel and delivering the fuel from said source under pressure to said first means, means to operate said pump at speeds variable with engine speed so that pump output changes within the certain range of engine speed, and means connected with said pump and responsive to changes in pump output connected with and operating said means for controlling the fuel ratio.
